KNITTING MACHINE

Frank G. Weisbecker, Glenside, Pa., assignor to
 Arcadia Hosiery Co., Lansdale, Pa., a corpora-
 tion of Pennsylvania

Application November 29, 1935, Serial No. 52,269

12 Claims. (Cl. 66—126)

The present invention relates to improvements in knitting machines, and more particularly to flat or straight full-fashioned knitting machines for hosiery and the like.

5 In knitting machinery of this type, comprising a series of sinkers adapted to successively advance behind a transversely moving yarn laying device including a carrier holder and yarn carrier, previous practice has been to employ a yarn guide, usually of steel or other rigid metal, in the form of a tube mounted upon and projecting from the lower end of the yarn carrier, and through which the thread or yarn is led. In normal operation of such a knitting machine, the sinkers, the top 10 edges of which are slightly above the level represented by the lower end of the guide tube, are caused to recede within a sinker bed prior to return movement of the yarn carrier. In actual practice, however, due to sticking of the sinkers, 15 or for other mechanical reasons, an individual sinker sometimes fails to properly recede, with the result that the guide tube of the yarn carrier comes into contact with the misplaced sinker and bends or fractures the same, consequently dis- 20 abling, temporarily at least, the knitting machine.

Since the sinkers are usually required to be made of comparatively thin material, such as thin sheet steel, the guide tube, if of unyielding steel, as is the customary practice, either breaks or 25 permanently deforms one or more of the sinkers so engaged. This breaking or deforming of the sinkers may result also in breakage of needles, wasting of yarn, spoilage of work, and excessive loss of time through the necessary shutdown of 30 the whole machine in order to remove and replace the damaged parts and readjust the machine. It will at once be apparent that the reduction in the amount of lost production time of 35 this kind is highly desirable and will improve the efficiency of the knitting machine.

Moreover, in the manufacture of various type stockings, it is necessary for the operator to set the yarn carriers in different positions. For example, in plating, where two yarns are used, it is necessary to set the plating yarn carrier higher 40 above the sinkers than it would be for straight type knitting, where only one yarn is used and where the carrier is set closer and lower to the sinkers. With the rigid guide tube of the prior art, much breakage and consequent loss of time often ensues before a proper adjustment of each 45 yarn carrier can be made. Furthermore, in work such as plating, the operator must use extreme care and caution in order to get perfect knitting. 50 During the preliminary adjusting period, there-

fore, the entire machine is run at a very slow speed in order to lessen the possibility of such breakage, because of the rigid character of the guide tube now generally used. Such slow running of the knitting machine results, necessarily, 5 in a corresponding loss in production and increase in overhead expenses.

According to this invention, a yarn laying device is provided with a yielding construction to permit the guide tube of the carrier or its tip to 10 be so deflected, upon encountering an obstruction in its path, such as a sinker or other yarn looping member, as to obviate the above enumerated 15 troubles and their attendant loss of time and efficiency.

This invention also provides a yielding carrier holder construction for use with conventional rigid yarn carriers, so that the latter may be 20 used interchangeably and may replace those used with the yielding carrier holder of this invention.

Another object of this invention is the provision of a yielding yarn laying device which will 25 permit its guide tube or tip to yield in the plane of its travel in event of engagement with a yarn looping member, such as a sinker, to avoid contact with other parts of the machine.

A further object is the provision of a yarn laying device with means for absorbing shocks and thrusts imparted by the machine to the guide tube or tip through the yarn laying device.

Other objects of this invention and a more detailed description of preferred embodiments of same, will appear below in the description of the accompanying drawing, in which:

Figure I is a front elevation of a form of the 35 invention, showing the yarn laying device in operative relation to the carrier bars, sinkers, dividers and needles of a straight knitting machine.

Figure II is a transverse sectional elevation taken on the line II—II of Figure I.

Figure III is a front elevation of another form 40 of yarn laying device.

Figure IV is a side elevation of the yarn laying device of Figure III and shows its relation, 45 when operating, to its supporting carrier bar and a sinker.

Figure V is a detail view in cross section, taken on line V—V of Figure IV.

In Figures I and II of the drawing, three of the carrier bars of a conventional full-fashioned 50 hosiery knitting machine are illustrated at 10, 10. Normally these machines are provided with seven such carrier bars, and the latter are longitudinally reciprocated for laying individual yarns controlled thereby between the needles and the 55

sinker bed and along the sinkers and dividers of the machine.

The sinker bed 11 of the machine has the usual sinkers 12 which alternate with dividers 13. These sinkers 12 and dividers 13 are movable relative to the sinker bed 11 and toward a row of needles for looping the laid yarn around the needles. The needles alternate with the sinkers 12 and dividers 13, and each needle is positioned similarly to the needle marked 14 in the drawing. In order to make the drawing clear, only one needle 14 has been illustrated in Figure I. In a side view, such as Figure II, only one needle 14 is normally visible and the other needles in the row are directly behind it. The sinkers 12 in their looping movement are normally projected across the path of movement of the yarn carriers from the full line to the broken line positions shown in Figure II.

In the conventional machine of today, the device carried by a carrier bar 18 for laying yarn along the sinkers 12 and dividers 13 comprises the well known rigid straight carrier holder and rigid yarn carrier. According to the embodiments shown in the drawing, the yarn laying device includes the conventional rigid yarn carrier 15, the latter being shown substantially as used in conventional practice. To properly position the lower straight yarn laying portion or end 16, including a guide tube 17, of the yarn carrier 15, it is usually angularly disposed with respect to the upper or carrier proper portion of the yarn carrier 15, so that a bend or vertex occurs at 18. In the reciprocation of the yarn carrier 15 for laying yarn, yarn carrier portion 16 and the tube 17 move in a plane which (looking at either Figure II or IV) is normal to the plane of the paper and passes through line marked *a—a*, while the upper portion of carrier 15 travels in an angularly disposed plane.

The conventional carrier holder is modified to permit shifting or rearward deflection of the yarn carrier portion 16 and guide tube 17 in their plane of movement and in either direction of travel or reciprocation in event of their engagement with a sinker 12 in the dotted line position shown in Figure II. For this purpose, as shown in Figures I and II, the carrier holder comprises two members 19 and 20 which are reversely bent intermediate their upper and lower ends to provide adjacent portions which are face to face and substantially parallel to yarn carrier end portion 16. The adjacent face to face portions of members 19, 20 are pivotally secured together by a rivet 21 with the pivotal axis normal to the plane (*a—a*) of movement of yarn carrier portion 16 and guide tube 17. Springs 22 on opposite sides of the pivot or rivet 21 are suitably secured to both members 19 and 20 to maintain them in normal, or straight position. These springs 22 also yield to permit the desired deflection of the yarn carrier portion 16 and guide tube 17 upon engaging a sinker or other obstruction in the dotted line position of Figure II. After the engaged obstruction is passed, the springs 22 realign the members 19 and 20 and restore the yarn carrier portion 16 to normal operative position. It is now clear that the carrier holder has a portion traveling in the plane marked by the line *b—b*, which is parallel to the plane *a—a*, and that the desired deflection or shifting of yarn carrier portion 16 is secured by providing the yielding connection in the carrier holder portion which moves in the plane *b—b*.

The carrier holder formed of members 19 and

20 is rigidly and detachably connected in conventional manner to both a carrier bar 18 and its yarn carrier 15 by screws or bolts 23 and 24 respectively.

In the form of the invention shown in Figures III to V, the carrier holder for the usual yarn carrier 15 comprises members 29, 30 similar to members 19, 20. In Figures III to V, however, members 29 and 30 are connected by one or more rubber rivets 31 which are vulcanized in place. The shanks of these rivets 31 may be of any suitable shape in cross section. In the figures, and particularly Figure V, the shanks of the rivets 31 are shown elongated or oval in cross section to correspond to the shape of the openings in the members 29, 30. Rubber rivets 31 permit the desired relative movement of members 29 and 30, while maintaining the adjacent parallel portions thereof in substantially face to face relation, so that yarn carrier portion 16 in deflecting will remain in substantially the plane of its movement *a—a*. After the deflecting obstruction is passed by portion 16, the rubber rivets 31 restore the yarn carrier to normal operative position.

Rubber rivets 31 have the additional function of reducing and absorbing shocks, thrusts, and vibrations passing to the guide tube 17 from the carrier bar 18 through the yarn carrier device and, therefore, provide for more even operation of the guide tube 17 in laying yarn. As a result, the machine will produce fabric with fewer defects than is possible where no such construction is provided.

While the drawing illustrates two embodiments of this invention, modifications of same will be apparent to the art. I, therefore, claim as part of my invention all variations of the illustrated embodiments within the limits of the appended claims.

In addition to the advantages of the yielding yarn laying device, described above, I have also found that knots and slubs will pass through such a device with much less likelihood of breakage of the thread or yarn than is the case with the stiff or rigid arrangement customarily employed. This result appears to be due to the fact that less jerking of the thread is caused by the passage of such knots or slubs through the yielding device than occurs with the stiff and unyielding form of construction.

By the use of my invention, also, the amount of spoiled work, and the resulting mending and waste of material is materially reduced when a machine so equipped is making what is called "split work". This split work consists of a cotton thread lapping over a silk thread the distance of two or four needles. In making split work with the regular carriers the latter are often set so high (to avoid striking the sinkers) that the machine fails to connect the two threads together, and spoiled work results. My improved form of device, however, may position the carrier extremely low, without danger of breakage, and such spoilage is substantially eliminated.

Other advantages and modes of practicing my invention will readily occur to one skilled in the art.

I claim:

1. The combination with a straight knitting machine having a sinker bed, a row of needles along said bed, and yarn looping members movable with respect to said bed and toward said needles, of a reciprocating yarn laying device comprising a yarn laying end portion movable in a plane along said row of needles and between

5 said needles and said sinker bed for laying yarn along said yarn looping members, said end portion being angularly disposed to the adjacent portion of the yarn laying device above and directly supporting said end portion, and a yielding connection above the said angularly disposed end portion and between parts of said yarn laying device movable in a plane different from the plane of movement of said yarn laying end portion, said connection permitting rearward deflection of said 10 end portion in its plane of movement in either direction of travel, in event of engagement of said end with a yarn looping member, said deflection allowing said end to ride past the engaged yarn looping member.

15 2. The combination with a straight knitting machine having a sinker bed, a row of needles along said bed, and yarn looping members movable with respect to said bed and toward said 20 needles, of reciprocating means for laying yarn along said yarn looping members, said means having spaced-apart portions for movement in parallel planes and an intermediate portion for movement in an angularly disposed plane, one of 25 said parallel-moving portions including a yarn laying end and the other of said parallel-moving portions including a yielding connection to permit rearward deflection of said yarn laying end in its plane of movement in event of engagement of 30 said end with a yarn looping member.

3. A combination as set forth in claim 1, in which the said connection includes a pivot and spring means for restoring said yarn laying end to normal operative position after deflection.

35 4. A combination as set forth in claim 1, in which the said connection is formed of elastic rubber.

40 5. A yarn laying device of the reciprocating type for straight knitting machines:—said device comprising a yarn carrier having its yarn laying end angularly disposed with respect to the carrier proper; and a carrier holder comprising a rigidly mountable member, a member detachably connected to said yarn carrier and rigidly supporting 45 same, and means articulating said members to provide for deflection of said yarn laying end in its operating plane of movement when moved relatively to said rigidly mountable member.

50 6. A yarn laying device of the reciprocating type for straight knitting machines comprising a yarn carrier having its yarn laying end angularly disposed with respect to the carrier proper, and a holder for said carrier, said holder comprising pivotally connected members having the pivotal axis substantially normal to the yarn laying 55 plane of movement of said angularly disposed carrier end when in use on a straight knitting machine.

7. A yarn laying device of the reciprocating type for straight knitting machines comprising portions in different substantially parallel planes and an intermediate portion in an angularly disposed plane, one of said parallel portions constituting a yarn laying end for the device, and another of said parallel portions including a pivotal connection having the pivotal axis substantially normal to the plane of movement of said yarn laying end when in use on a straight 10 knitting machine. 5

8. A yarn laying device for straight knitting machines comprising a pair of members, one of which includes a yarn laying guide end, and elastic means having the characteristics of rubber, securing said members together to permit their relative angular and longitudinal movement and serving as a shock and thrust absorber for the yarn laying guide end. 15

9. A holder for a reciprocating yarn carrier 20 of a straight knitting machine comprising a rigidly mountable member, a member for detachably supporting a yarn carrier, and means articulating said members to provide for shifting of the yarn laying end of the yarn carrier in its 25 operating plane of movement when moved relatively to said rigidly mountable member and to restore said yarn laying end to normal position. 20

10. A yarn carrier holder for straight knitting machines comprising a rigidly mountable member, a member for rigidly supporting a yarn carrier, said members having reverse bends to provide parallel adjacent portions, and means for flexible securing said portions together in face to face relation and permitting relative angular 35 movement between said members while maintaining said face to face relation. 30

11. A yarn carrier holder for straight knitting machines comprising a rigidly mountable member, a member for rigidly supporting a yarn carrier, and adapted to be detachably connected thereto, and means formed of rubber for securing portions of said members in face to face relation and permitting relative movement between said members while maintaining said face to face relation, said rubber means serving also to absorb shocks, thrusts and vibrations passing between 40 45 said members. 45

12. A yarn carrier holder for straight knitting machines comprising a rigidly mountable member, a member for rigidly supporting a yarn carrier and adapted to be detachably connected thereto, and means comprising at least one rubber rivet for securing portions of said members in face to face relation and permitting relative 50 movement between said members while maintaining said face to face relation. 55
